UNITED STATES PATENT OFFICE.

WILLIAM M. FOLBERTH AND FREDERICK G. FOLBERTH, OF CLEVELAND, OHIO.

WINDSHIELD CLEANER.

Application filed July 3, 1926. Serial No. 120,378.

This invention relates to a windshield cleaner of the fluid pressure or suction operated type, and more especially to the valve mechanism for controlling the application of operating pressure to the piston construction.

Various attempts have been made to provide a simple and efficient automatic valve mechanism for connecting the suction passage alternately to the cylinder passages which lead to the opposite ends of the motor cylinder, but their assembly and the mounting of their parts have required the use of special tools in the hands of highly skilled workmen, or where the assembly could be expediently effected the construction and arrangement did not insure a perfect action especially after considerable wear on the parts. The present invention aims to provide an automatic valve mechanism which may be readily and expediently assembled without the aid of any tools, and which will insure a perfect seating of the valve, and it has for one of its objects to provide an improved mounting for the valve carrier whereby during the normal operation of the valve carrier to move the valve back and forth on the seat, said valve will be urged more firmly to engage its seat. A further object of the invention is to mount the valve on its carrier so as to readily accommodate itself to its seat even though the movement of the carrier should be irregular or untrue. Another object of the invention is to provide an actuator for the valve carrier which will be normally held against displacement, but which by manual manipulation may be readily mounted and dismounted. Finally, the invention has for its object to improve the general assembly and arrangement of the valve carrier, its actuator and the related parts for the efficient working of the cleaner motor.

In the drawings;

Fig. 1 is a transverse sectional view through a cleaner motor constructed in accordance with the present invention, and being shown applied to a windshield, the latter being in fragment;

Fig. 2 is a longitudinal sectional view through the improved motor;

Fig. 3 is a horizontal detailed view about on line 3—3 of Fig. 2 showing the mounting of the valve on its carrier;

Fig. 4 is a similar view about on line

4—4 of Fig. 2, further disclosing the valve carrier and its mounting;

Fig. 5 is a detailed perspective view of the valve carrier;

Fig. 6 is a similar view of the actuator. 60

The motor, in this particular construction comprises a cylinder formed of two cupped sections 1 clamped together at their open ends by an encircling band 2, the ends of which are secured to a cover plate or body member 3. The body member is provided on its inner face with a bearing sleeve 4, and beneath this sleeve said face is provided with spaced cylinder ports 5 and an interposed suction port 6, said suction port 70 being alternately connectible to the cylinder ports for establishing communication with the respective ends of the cylinder, as by means of pipes 7 which are connected to the ports 5. This type of motor is well known 75 in the windshield cleaner art, and is shown in our former application, Serial No. 701,519, filed March 24, 1924, of which this application is an improvement.

Journaled within the bearing sleeve 4 is a 80 wiper actuating shaft 8 which extends transversely through the cylinder or casing of the motor and supports a wiper 9 on its outer end. This shaft has fixed thereto within the cylinder a segmental gear 10 85 which meshes with a rack 11 connecting the spaced pistons 12, whereby as the latter are reciprocated within the cylinder, such motion will be translated into the desired oscillatory motion for operating the wiper. 90 The valve actuating mechanism comprises a valve carrier 13 and a slide or actuator 14, together with an interposed connecting spring 15. In the form shown the valve carrier is of an open frame construction 95 having a central opening 16 by which the carrier may be passed over the projecting bearing sleeve 4 and hung or suspended on a knife or bearing edge 17. This bearing edge is formed on the upper side of the 100 bearing sleeve at an inclination extending downwardly toward the inner face of the body member 3 whereby the carrier frame will be urged toward the valve seat. The lower side of the valve carrier frame is provided with an opening 18 adapted to receive the stem or shank 19 of the valve 20, said frame being further provided with a ridge or bearing edge 21 on which the valve is adapted to rest in more or less of a rockable 110

- manner whereby the valve will uniformly engage its seat regardless of any untrue action or operation of the valve carrier. A stop portion 22 depends from the carrier frame 5 to cooperate with spaced stops 23 on the body member 3 to define the extent of movement of said frame, said stop portion having an outwardly upturned terminal 24 to which one end of the spring 15 is attached.
- 10 On the under side of the bearing sleeve 4 and offset outwardly toward the free end thereof, relative to the terminal 24, is a guide in the form of a groove 25, and in this groove is mounted the lower frame member 26 of the actuator 14. This frame member is provided centrally with a perforated ear 27 to which the upper end of the spring 15 is attached, and the relation of the ear 27 and the terminal 24 is such as to normally dispose the spring 15 at such an inclination as to force the valve toward the valve seat. The actuator is herein illustrated as being of a substantially rectangular design, having an elongated opening for operatively receiving the bearing sleeve 4. The upper frame member 28 has a centrally offset portion 29 for receiving said bearing sleeve in mounting the actuator thereon. The dimensions of the elongated opening of the actuator frame are such that the upper frame member 28 will hold the actuator against displacement except when the latter is moved to a central position wherein the offset 29 is opposite said bearing sleeve 4, 25 in which position the actuator may be depressed against the compression spring 15 for displacing the lower frame member 26 from its guide 25.
- 30 The action of the spring is to push downwardly on the carrier frame, in the position shown in Fig. 1, and this tendency is taken advantage of to effect a firmer seating of the valve by reason of the fact that the bearing edge 17 inclines downwardly, whereby any downward pressure on the carrier frame would tend to shift the carrier frame toward the inner face of the body member 3. To support the carrier in an operative position, and to also reduce the frictional contact between the carrier frame and the inner face of the body 3, said carrier frame is provided with spaced balled projections 30 which serve to retain the upper end of the carrier frame at substantially the same space from the inner face of the body member as the lower end of the frame is spaced therefrom by the interposed valve 20. A pair of outstanding fingers 31 are provided on the sides of the opening 16, and these are adapted to engage the bearing sleeve 4 in the event that the carrier frame tilts at either side from the inner face of the body member, thereby serving to steady and hold the frame in its true operative position.
- 35 40 45 50 55 60 65 70 75 80 85 90 95 100 105 110 115 120 125 130
- 65 In practice the valve mechanism is assem-
- bled before the shaft 8 is inserted through its bearing sleeve 4, and in the assembly of said mechanism the carrier frame 13 with its valve is suspended from the bearing edge 17, following which the actuator is passed over the outer end of the bearing sleeve, with the latter entering the offset 29, until the frame bar 26 comes opposite the guide 25, at which time said frame bar is moved upwardly into the guide groove. The actuator frame is now shifted to bring the bearing sleeve 4 into one or the other of the restricted end portions of the elongated frame opening. The spring may be connected either before or after the mounting of the actuator.
- In the operation of the valve mechanism, the actuator is shifted by and during the movement of the piston assembly 12, the rear piston engaging the adjacent end of the actuator as it nears the completion of its stroke and shifts the actuator to move its attached end of the spring to the other side of the plane which includes the bearing edge and the terminal 24, or, in other words, beyond dead center. At this point in the operation, the spring expands and shifts the valve carrier against the opposite stop 23 in which position the valve connects the suction port to the uncovered cylinder port 5 whereby the air behind the piston will begin to be withdrawn while atmospheric pressure will be admitted through the formerly closed and now uncovered or open port 5 to its respective zone in the cylinder. In this connection atmospheric pressure always obtains within the cylinder between the two piston elements by reason of the air leak joints between cup members 1, the band 2, the body member 3 and the bearing for the shaft 8.
- What is claimed as new is:—
1. In an automatic windshield cleaner motor, a cylinder, a pair of connected pistons reciprocable therein, a body member extending into the cylinder between the pistons and provided on its inner face with a shaft bearing sleeve and a valve seat through which a suction port and spaced cylinder ports open, said cylinder ports communicating with the opposite ends of the cylinder, a valve movable over the valve seat for connecting the suction port alternately with the spaced cylinder ports whereby the opposite ends of the cylinder are alternately placed in communication through the suction port with a source of suction, the side of said bearing sleeve remote from the valve seat being provided with a bearing edge which inclines toward the valve seat and the inner face of said body member, a valve carrier having an opening through which said bearing sleeve projects, said carrier pivoting on said bearing edge and engaging the valve to move the same back and

- forth over its seat, the side of said bearing sleeve adjacent the valve seat being provided with a guide extending lengthwise of the cylinder, an actuator slidable by said pistons along the guide, and a spring compressed between said carrier and said actuator and alternately positionable by the latter to move the carrier back and forth.
2. A valve actuating mechanism for automatic windshield cleaner motors, comprising a body member having a valve seat on one face and an overhanging bearing edge spaced from and inclining toward said face and said seat, a valve engaged on the seat, a valve carrier pivoted on said bearing edge and engaged with said valve, an actuator mounted on the body member for movement back and forth by a moving part of the cleaner motor, and a spring connecting the actuator and carrier and cooperating with said bearing edge for urging the valve toward its seat, said spring being operatively positioned by said actuator for moving said carrier.
3. A valve actuating mechanism for automatic windshield cleaner motors, comprising a body member having a valve seat on one face and an overhanging bearing edge spaced from and inclining toward said face and said seat, a valve engaged on the seat, a valve carrier pivoted on said bearing edge and engaged with said valve, and means for oscillating the carrier including a resilient member acting to pull said carrier down the inclined bearing edge for urging the valve against its seat.
4. In automatic valve mechanism for windshield cleaner motors, a body member having a valve seat on its inner face and an overhanging bearing edge inclined toward the seat, a valve carrier pivoted on said bearing edge, a valve interposed between the valve seat and valve carrier and movable by the latter on said seat, said carrier having a spacing projection adjacent its pivotal mounting for spacing the carrier from the inner face of said body member, and means for oscillating said carrier and urging the valve to its seat.
5. In automatic valve mechanism for windshield cleaner motors, a body member having a valve seat, a valve carrier pivoted on said body member and formed with a bearing edge, a valve connected to the carrier and movable thereby on said seat, said valve having rockable support on said bearing edge whereby said valve will accommodate itself to said seat relative to said carrier, and means for actuating the carrier.
6. In automatic valve mechanism for windshield cleaner motors, a body member having a valve seat, a valve carrier pivoted on said body member and formed with a valve receiving opening and a bearing edge adjacent the opening, a valve pivotally rest-
- ing on the bearing edge and having a part engaging in the opening of the carrier, said valve being movable over the seat by said carrier, and resilient means for actuating the carrier from a moving part of the cleaner motor.
7. In automatic valve mechanism for windshield cleaner motors, comprising a body member having a valve seat on its face, a bearing member projecting from the face of said body member and formed on one side with a transverse guide, a valve engaged on the seat of said body member, a reciprocating actuator operable along said guide from a moving part of the cleaner motor and having an elongated opening through which said bearing member projects, one wall of the elongated opening slidably engaging the guide of said bearing member and the other wall of the elongated opening being centrally offset to receive the bearing member whereby the first wall may be engaged with its guide, and means interposed between the actuator and the valve for moving the latter by the actuator, said means acting to hold the actuator operatively related to its guide.
8. An automatic valve mechanism for windshield cleaner motors, comprising a body member having a valve seat on its face, a bearing member projecting from the face of said body member and formed on one side with a transverse guide, a valve engaged on the seat of said body member, an actuator movable back and forth on said guide from a moving part of the cleaner motor and having an elongated opening through which said bearing member projects, one wall of the elongated opening slidably engaging the guide of said bearing member and the other wall of the elongated opening being centrally offset to receive the bearing member whereby the first wall may be engaged with its guide, said actuator being held against displacement by said bearing member when the latter is in either end of the elongated opening, a valve carrier pivoted to the body member for moving the valve on its seat, and a spring interposed between the carrier and the actuator and adapted to be positioned by the latter for shifting the carrier back and forth, said spring normally holding the actuator at either limit of its movement in which position said bearing member is disposed in the corresponding end of the elongated opening whereby the actuator is held against displacement from its guide by said bearing member.
9. A valve mechanism for automatic windshield cleaner motors, comprising a body member having a valve seat on one face and a stop portion thereadjacent, a bearing member projecting from said face and having a knife edge, a valve operable on the seat, a carrier frame hung over said

knife edge of the bearing member and supporting the valve, said frame having a stop part engageable with said stop portion for limiting its movement, said frame encircling 5 said bearing member and having portions adapted to engage the same to assist in maintaining the frame operative, an actuator movably supported by said body member, and a spring connecting the actuator to the 10 stop part of the carrier and adapted to be positioned by the actuator for effecting a shift of said carrier.

10. An automatic valve mechanism for windshield cleaners, comprising a body 15 member having a valve seat on one face and a projecting bearing part, a valve movable on the seat, a carrier frame passed over the bearing part and pivotally hung thereon for supporting the valve for movement on its 20 seat, said frame having out-turned fingers

adapted to engage said bearing part to aid in maintaining the frame operative, and means for oscillating the frame.

11. An automatic valve mechanism for windshield cleaner motors comprising a 25 body member having a valve seat, a valve carrier pivotally hung on the body member and having a part movable over the valve seat, said valve carrier part being formed with a bearing edge, a valve engaged with 30 said valve seat and movable thereover back and forth by said valve carrier part, said valve connected to said carrier part and having a rockable support on said bearing edge whereby said valve will accommodate 35 itself to said valve seat, and means for actuating the carrier from a moving part of the cleaner motor.
